SEWING MACHINE

Charles E. Colegrove, Lakewood, Ohio

Application April 10, 1933, Serial No. 665,297

11 Claims. (Cl. 112—260)

This invention relates to a sewing machine and more particularly to the construction of the cover plate for the hand-hole opening in the bed plate of the machine.

5 An object of the present invention is to provide a cover plate for the hand-hole opening in the bed plate of a sewing machine which is so constructed that it may be readily moved to open or closed position and which will have no parts projecting above the level or beyond the edge of the bed plate in either position.

Another object is to provide in a sewing machine a cover plate for the hand-hole opening which must be moved to its fully closed position in order that it will not return automatically to its open position.

A further object is to provide in a sewing machine a cover plate for the hand-hole opening which is of simple construction, is permanently connected to the bed plate of the machine, is substantially out of the way below the level of the bed plate of the machine when moved to the open position, and which may be quickly and easily operated or moved into either the closed or open position.

A still further object is to provide in a sewing machine a downwardly swinging cover plate for the hand-hole opening and with which is associated operating and holding means of such character that when the plate is in the closed position it cannot be opened, released or swung to open position by a downward pressure applied to the upper surface of the plate itself but only by manipulation of the operating means.

35 Further and additional objects and advantages will become apparent hereinafter during the following detailed description of an embodiment of the invention which is illustrated in the accompanying drawing wherein:

40 Figure 1 is a fragmentary top plan view of the bed plate of a sewing machine showing the hand-hole cover plate in closed position adjacent the needle plate.

45 Fig. 2 is a fragmentary bottom plan view taken from the under side of Fig. 1.

Fig. 3 is an irregular longitudinal sectional view through the bed plate and hand-hole cover plate and is taken substantially on line 3—3 of either Fig. 1 or 2, looking in the direction of the arrows.

50 Fig. 4 is an end elevational view taken from the right hand side of Fig. 1 as viewed in the drawing and showing a hand-hole cover plate in closed position in full lines and in open position in dotted lines.

55 Fig. 5 is a fragmentary detailed sectional view

similar to Fig. 3 and showing by dotted or full lines different conditions of certain of the parts of the actuating and locking means for the hand-hole cover plate, and

Fig. 6 is a detached diagrammatic view, the hand-hole cover plate being indicated in the open position by dotted lines, while the actuating and locking mechanism for the plate is shown in full lines.

The bed plate of a sewing machine bed is indicated at 10 and is provided adjacent one of its ends with a needle plate 11 having therein slots for the toothed feed 12 of the machine and an opening for the needle carried by the reciprocating needle bar (not shown) as is well understood in the art. In accordance with the usual construction of a sewing machine, the shuttle is arranged beneath the needle plate 11 in a position to cooperate with the reciprocating needle, a rotary shuttle 13 being shown in the drawing by way of illustration only.

The bed plate 10 is provided with an opening extending inwardly from the right hand end of the bed, as viewed in the drawing, which opening should be of sufficient size to afford convenient access for the operator to the shuttle of the machine in order to adjust the same or to mount a bobbin case therein. The opening in the bed plate just referred to is closed by a plate 14 of such size as to extend from the end of the bed to the needle plate 11 and to be capable of swinging downwardly into the opening and substantially beneath the bed. The cover plate 14 is secured at its outer or right hand edge (as viewed in Fig. 1) to a strip 15 having at its opposite ends trunnions 16 extending into suitable recesses formed in the bed plate 10 at the sides of the hand-hole opening therein.

Beneath the hand-hole opening in the bed plate 10 a beam 17 is arranged and has at its opposite ends laterally turned portions 18 and 19 provided with extensions below the lower edge of the beam 17 which are pivotally connected by suitable pivots 20 extending through openings 21 in the extensions to depending members 10a carried by the bed plate 10 and located adjacent the hand-hole opening. The upper edge of the beam 17 intermediate its ends is provided with a laterally extending portion 22 at the outer end of which is an upwardly extending tab 23. The extension on the portion 19 is extended beyond the opening 21 and is arranged to engage a stop pin 24 carried by the member 10a of the bed when the beam 17 has been moved to a position wherein the cover plate 14 is free to swing downwardly

to open position, as will later be explained. The portion 19 also extends slightly above the upper edge of the beam 17 and is provided with an in-turned flange 25 secured to the under side of an actuating member 26 which, when the cover plate 14 is in closed position, will be flush with the upper surface thereof and will be arranged in a recess formed in the plate 14 adjacent the front side of the machine. When the cover plate 14 is in fully closed position stop lugs 27 secured to the under side of the plate will engage beneath the needle plate 11 and form definite stops insuring the proper position of the cover plate 14 in the closed position. The actuating member 26 will also be in a horizontal position flush with the cover plate 14, while the upwardly extending tab 23, at the end of the portion 22 of the beam 17, will be in engagement with the under side of the cover plate at a point slightly past the vertical plane including the longitudinal center line of the pivots 20 for the portions 18 and 19 of the strip and on the opposite side of the transverse center line of the cover plate from the axis of the trunnions 16. This engagement between the tab 23 and the cover plate 14 will hold the cover plate in its upper or closed position and it will be seen that any downward pressure exerted upon the plate 14 will be ineffective to open the plate and will press upon the tab 23 in a downward direction lying substantially in the vertical center line of the pivots 20. When it is desired to open the cover plate 14 to afford access to the shuttle, the operator merely presses downwardly on the right hand end (as viewed in the drawing) of the actuating member 26 with the result that the strip 17 is swung in a clockwise direction on its pivot and the tab 23 is moved to the opposite side of the vertical plane of the longitudinal center line of the pivots 20 to an off-center position, whereupon the weight of the cover plate and of the beam 17 and actuating member 26 will cause the cover plate to swing downwardly by gravity to the open position, as indicated in dotted lines in Figs. 3, 4 and 6, the end of the portion 19 engaging with the stop pin 24 to limit the downwardly swinging movement of the cover plate and the actuating member. It is only necessary that the actuating member 26 be rocked slightly from its horizontal position to move the tab 23 to the off-center position previously referred to, and to allow the actuating member and the cover plate to swing down by gravity, such position to which the actuating member 25 should be moved for this purpose being illustrated in Fig. 5 in full lines.

When the cover plate 14 is in the open position, the left hand end, (as viewed in the drawing) of the member 26 will extend just slightly above the level of the bed plate 10, as shown in dotted lines in Fig. 3 and there will be sufficient space between this end of the member and the downwardly inclined cover plate to allow a finger of the operator to be inserted therebetween to move the member 26 to its full line position, as shown in Fig. 5, at which time the cover plate 14 will be in a substantially closed position. It will be seen that after the member 26 has been moved to this position downward pressure exerted upon the left hand end of the member, as viewed in the drawing, will swing the beam 17 and the tab 23 still further to bring the tab slightly beyond the vertical plane of the longitudinal center line of the pivots 20, as viewed in Fig. 3, at which time the cover plate will be locked in the fully closed position.

Although a preferred embodiment of the invention has been illustrated and described herein, it should be understood that the invention is susceptible of various modifications and adaptations within the scope of the appended claims. 5

Having thus described my invention, I claim:

1. In combination with a sewing machine bed having a hand-hole opening therein, a cover plate for said opening pivotally connected to said bed and adapted when in closed position to fill said opening and lie substantially flush with the upper surface of the bed and when in open position to extend downwardly through said opening, and a single means operable from the upper side of the bed for moving said cover plate to closed position and for maintaining the same therein, said means including a member separate from but engaging the under side of said cover plate. 10

2. In combination with a sewing machine bed having a hand-hole opening therein, a cover plate for said opening pivotally connected to said bed and adapted when in closed position to fill said opening and to lie substantially flush with the upper surface of the bed and when in open position to extend downwardly through said opening, and a single means for moving said cover plate to closed position and for maintaining the same therein and for effecting opening movement thereof including an actuating portion operable from the upper side of the bed and a portion separate from but engaging the under side of said cover plate. 20

3. In combination with a sewing machine bed having a hand-hole opening therein, a cover plate for said opening pivotally connected at one of its ends to said bed and adapted when in closed position to fill said opening and to lie substantially flush with the upper surface of the bed and when in open position to extend downwardly through said opening, and a single means for moving said cover plate to closed position and for maintaining the same therein and for effecting opening movement thereof including a portion engaging the under side of said cover plate on the opposite side of the transverse center line thereof from the side upon which is its pivotal axis. 30

4. In combination with a sewing machine bed having a hand-hole opening therein, a cover plate for said opening pivotally connected at one of its ends to said bed and adapted when in closed position to fill said opening and to lie substantially flush with the upper surface of the bed and when in open position to extend downwardly through said opening, and means for moving said cover plate to closed position and for maintaining the same therein and for effecting opening movement thereof including an actuating member operable from the upper side of the bed and a member engaging the under side of said cover plate when the latter is in the closed position on the opposite side of the transverse center line thereof from its pivotal axis. 40

5. In combination with a sewing machine bed having a hand-hole opening therein, a cover plate for said opening pivotally connected to said bed and adapted when in closed position to fill said opening and lie substantially flush to the upper surface of the bed and when in open position to extend downwardly through said opening, and means for moving said cover plate to closed position and for maintaining the same therein and for effecting opening movement thereof including an independently pivoted member separable from but engaging the under side of the cover plate when the latter is in the closed position at a point 50

70

75

contiguous to the vertical plane passing through the pivotal axis of said member.

6. In combination with a sewing machine bed having a hand-hole opening therein, a cover plate for said opening pivotally connected at one of its ends to said bed and adapted when in closed position to fill said opening and lie substantially flush with the upper surface of the bed and when in open position to extend downwardly through said opening, and means for moving said cover plate to closed position and for maintaining the same therein and for effecting opening movement thereof including a pivoted member engaging the under side of the cover plate when in the closed position at a point contiguous to the vertical plane passing through the pivotal axis of said member and on the opposite side of the transverse center line of said cover plate from the pivotal axis of the latter.

7. In combination with a sewing machine bed having a hand-hole opening therein, a cover plate for said opening pivotally connected to said bed and adapted when in closed position to fill said opening and lie substantially flush with the upper surface of the bed and when in open position to extend downwardly through said opening, said cover plate being provided in one of its marginal edges with a recess, and means for moving said cover plate to closed position and for maintaining the same therein and for effecting opening movement thereof including an actuating member which when the cover plate is closed substantially fills said recess and lies flush with the upper surface of said cover plate.

8. In combination with a sewing machine bed having a hand-hole opening therein, a cover plate for said opening pivotally connected to said bed and adapted when in closed position to fill said opening and lie substantially flush with the upper surface of the bed and when in open position to extend downwardly through said opening, said cover plate being provided in one of its marginal edges with a recess, and means for moving said cover plate to closed position and maintaining the same therein and for effecting opening movement thereof including a member having a portion engaging the under side of said cover plate and an actuating portion substantially filling said recess when the cover plate is in the closed position and having its upper surface substantially flush with the upper surface of said cover plate.

9. In combination with a sewing machine bed

5
having a hand-hole opening therein, a cover plate
for said opening pivotally connected at one of
its ends to said bed and adapted when in closed
position to fill said opening and lie substantially
flush with the upper surface of the bed and when
in open position to extend downwardly through
said opening, said cover plate being provided in
one of its marginal edges with a recess, and
means for moving said cover plate to closed posi-
tion and for maintaining the same therein and
for effecting opening movement thereof including
a pivoted member having a portion engaging the
under side of said cover plate when the latter is
fully closed at a point contiguous to the vertical
plane passing through the pivotal axis of said
member and on the opposite side of the trans-
verse center line of said cover plate from the
pivotal axis of the latter and an actuating por-
tion arranged to substantially fill said recess when
the cover plate is in the closed position with its
upper surface substantially flush with the upper
surface of said cover plate.
10
15
20

10. In combination with a sewing machine bed having a hand-hole opening therein, a cover plate for said opening pivotally connected at one of its ends to said bed and adapted when in closed position to fill said opening and lie substantially flush with the upper surface of the bed and when in open position to extend downwardly through said opening, and means for moving said cover plate to closed position and for effecting opening movement thereof including a pivoted member having a portion engaging the under side of said plate when the latter is fully closed at a point contiguous to the vertical plane passing through the pivotal axis of said member and on the side of said plane opposite to the pivotal axis of the cover plate.

11. In combination with a sewing machine bed having a hand-hole opening therein, a cover plate for said opening pivotally connected to said bed and adapted when in closed position to fill said opening and lie substantially flush with the upper surface of the bed and when in open position to extend downwardly through said opening, separately pivoted means for moving said cover plate to closed position and for maintaining the same therein and for effecting opening movement thereof, and means for limiting movement of said pivoted means during the opening movement of said cover plate.

CHARLES E. COLEGROVE.
